ELECTRICAL BEACON EQUIPMENT

Carlton L. Jacobs, Houston, Tex., assignor to Tideland Specialty Co. Inc., Houston, Tex., a corporation of Texas

Application June 17, 1957, Serial No. 666,138

9 Claims. (Cl. 315—93)

This invention relates to electrical beacon equipment and more particularly to electrical timer and lamp changing mechanism employed in flashing beacons.

The invention finds particular application in connection with electrical beacon equipment of the flashing type, which must be capable of dependable operation over long periods of time, and in which the on and off periods of the light must be accurately determined and are of relatively short duration.

In electrical beacon light equipment and especially flashing beacons wherein size and weight are important factors, great difficulty has been encountered in providing timing and lamp changing mechanism which is positive and accurate in operation and in which the power consumed is low.

The present invention has for an important object the provision of electrical beacon equipment including lamp changing mechanism which comes into operation upon the burning out or defective operation of an electric lamp which is being used to replace the lamp with a new one.

Another object of the invention is to provide electrical beacon equipment embodying lamp changing mechanism which is operable upon the placing in circuit of a lamp which is defective or which consumes current for inefficient operation to replace such lamp with another lamp.

A further object of the invention is the provision of electrical beacon equipment of the flashing type having timing mechanism for controlling the on and off time of the lamp and wherein means is embodied which is operable upon failure of the timing mechanism to cause the lamp to remain continuously lighted.

Another object of the invention is the provision of electrical beacon equipment embodying lamp changing mechanism which is effective upon the burning out of a lamp to replace the same with a minimum of delay in, or suspension of, the operation of the beacon.

Another object of the invention is to provide electrical beacon equipment including lamp changer mechanism which is operable upon the burning out of one lamp to place another lamp in circuit, and including means for shutting off the operation of the lamp changer mechanism when the supply of lamps has been exhausted.

A still further object of the invention is to provide electrical beacon equipment which is of simple design and rugged construction, capable of withstanding the rough treatment and extreme conditions of exposure to which such equipment is likely to be subjected.

The above and other important objects and advantages of the invention may best be understood from the following detailed description constituting a specification of the same, when considered in conjunction with the annexed drawings. In the drawings the single figure is a circuit diagram showing the electrical circuits of the timing and lamp changing mechanism of the invention.

Referring now to the drawings in greater detail, the invention comprises electrical timer mechanism of the rotary cam actuated type with which is combined lamp

changer mechanism including a rotatable lamp carrying turret and means for operating the same upon the burning out of one lamp to move another lamp into operating position.

5 The timing mechanism of the invention embodies cam actuated switch mechanism designated generally by the numeral 10 which includes a cam 12, having an operating connection with an electrical motor, not shown, whereby the cam is rotated at a predetermined speed, the cam being 10 positioned to periodically actuate the switch arms 14, 16 and 18 of switch mechanism by which the electrical timing circuits are opened and closed.

The motor by which the cam 12 is rotated is connected to a source of electrical current, such as a battery 13, of 15 any suitable type, through conductors 20 and 22. The switch arm 14 is also connected to one terminal of the battery 13 through conductor 22 and a conductor 24. The opposite terminal of the battery 13 is connected to the switch arm 18 through conductor 20, conductor 26, a relay coil 28 of a hold out relay and conductor 30. A condenser 32 is connected across the relay coil 30 for a purpose to be pointed out hereinafter.

The switch arm 16 is connected to the conductor 22 through a conductor 36, armature 34 of the hold out relay 25 and conductor 40, the armature 34 being positioned to be actuated by relay coil 28 upon energization thereof. The armature 34 will be held out of contact with the contact 38 to open the circuit between the battery and the switch arm 16 when coil 28 is energized and will 30 be in contact with contact 38 when coil 28 is deenergized to close the circuit between the battery and the switch arm 16.

The switch arms 14, 16 and 18 have contact elements 35 15, 17 and 19, respectively, which are arranged so that the arm 14 makes contact with the arm 16 before the arm 16 makes contact with the arm 18, the cam 12 being operable to first move arm 14 into contact with arm 16 through contact elements 15 and 17 and thereafter to move arms 14 and 16 to move the arm 16 into contact 40 with arm 18 through contact elements 17 and 19.

An electric lamp 42 is connected to the above described timer mechanism through a conductor 46, connected to the switch arm 17, a relay coil 48, conductor 50 and return to battery 13 through conductors 52 and 58. In 45 the operation of the timing mechanism, when the cam 12 is rotated, the switch arm 14 will first make contact with switch arm 16. Current will then flow from battery 13 through conductors 22 and 24, switch arms 14 and 16, conductor 46, coil 48 and conductor 50 to lamp 42 and return through conductors 52 and 58, to light the lamp. Switch arms 14 and 16 will also be moved into contact with switch arm 18, whereupon current may flow from battery 13 through conductors 22 and 24, switch arm 14, contacts 15, 17 and 19, switch arm 18 and conductor 30 to 50 relay coil 28 and return through conductors 26 and 20, to energize coil 28 to hold relay armature 34 in open position.

The condenser 32 will be charged during the time that the cam 12 holds the contacts 15, 17 and 19 closed, and 55 this condenser has a capacity sufficient to keep the coil 28 energized during the off time of the lamp, so that the relay armature 34 remains in open position so long as the timer is operating. Should the timer motor fail with the contacts 15, 17 and 19 closed, the light will remain continuously lighted. On the other hand, should the motor fail with the contacts 15, 17 and 19 open, then the coil 28 will be deenergized as soon as the condenser 32 has become discharged and armature 34 will close so that current from the battery 13 will then be continuously supplied to the lamp 42 through conductor 36, armature 34 and conductor 40. By this arrangement

failure of the timing mechanism results in the lamp 42 remaining continuously lighted.

The lamp changer mechanism may be of a well known type having a lamp carrying turret provided with a number of lamps arranged to be successively moved into position in circuit with the battery and timing mechanism, and mechanism for actuating the turret upon burning out or failure of the lamp in circuit. The details of construction of the lamp changer mechanism are not shown herein. The mechanism by which the turret is actuated upon burning out of a lamp to move the next lamp into position includes an electric motor 44 having an operating connection with the turret and which is connected into a circuit to receive current from the battery 13 upon the burning out of a lamp 42 of the turret.

The lamp changer circuit of the invention includes a relay of the opposed coil type having an armature 62 and coils 48 and 70 which are so arranged and constructed that the armature 62 will remain in open position as long as both of the coils are supplied with current. The coil 48 is connected in circuit with the lamp 42 through conductors 46 and 50 and the coil 70 receives current through conductors 46 and 58, so that both coils will be energized as long as lamp 42 is lighted. Should lamp 42 burn out, coil 48 will no longer receive current but coil 70 will continue to receive current through conductors 46 and 58 and the armature 62 will then be moved to closed position.

The motor 44 is connected in circuit with the battery 13 through conductor 46, conductor 60, armature 62, conductors 64, contacts 75 and 77 of a time delay relay, conductor 68 and return to battery through conductors 58 and 20.

During normal operation of the beacon with the lamp 42 lighted current flows through both of the coils 48 and 70, which are arranged so that their magnetic fields are opposed, and the armature 62 remains open. The lamp changer relay is of a relatively slow acting type so that the armature 62 does not open during the interval between flashes of the lamp 42. In the event that the lamp 42 burns out, however, the coil 48 no longer is energized and armature 62 is closed by coil 70 which continues to receive current. Pulsating current is then supplied to the motor 44 through conductor 46, conductor 60, armature 62, conductor 64, relay contacts 75 and 77, conductor 68 and return through conductors 58 and 20 to actuate the lamp turret to move the next lamp into operating position. As soon as the new lamp reaches operating position the supply of current is restored to coil 48 and the armature 62 moves to open position cutting off the current to motor 44 and stopping the turret.

The time delay relay having the contacts 75 and 77 in circuit with the motor 44 includes a heat sensitive element 73 which carries the contact 75 and which is movable under the influence of a rise in temperature to move the contact 75 out of contact with contact 77 to open the motor circuit. The time delay relay also has a heating element 67 connected to receive current through conductor 64 and conductor 58 and located to supply heat to the heat sensitive element 73.

In the event that all of the lamps of the turret of the lamp changer mechanism should be burned out the motor 44 will continue to operate to operate until the heater 67 has heated the element 73 sufficiently to cause the contact 75 to be moved out of contact with contact 77, whereupon the motor circuit will be opened to stop the turret. The heat sensitive element 73 and heater 67 are so selected that the motor 44 will be operated only long enough to rotate the turret a predetermined number of revolutions after all of the lamps are burned out, thus preventing undue wear on the turret and depletion of the battery due to continuous rotation of the turret.

It will thus be seen that the invention constructed and arranged as described above provides electrical beacon equipment of the type having a rotatable lamp carrier

or turret provided with a plurality of electric lamps and movable to successively position the lamps in operating position, there being an electric motor for actuating the carrier and means being provided for automatically closing the motor circuit when the lamp circuit is opened by the burning out of one lamp to cause a new lamp to be moved into position and for opening the motor circuit when the lamp circuit is closed by the new lamp.

While the invention has been disclosed herein in connection with a certain specific embodiment of the same, it will be understood that this is intended by way of example only, and that various changes can be made in the arrangement of the parts within the spirit of the invention and the scope of the appended claims.

Having thus clearly shown and described the invention, what is claimed as new and desired to secure by Letters Patent is:

1. Electrical beacon equipment comprising an electric lamp, an electrical current source, an electrical circuit connecting the lamp and source, switch means for opening and closing the circuit at predetermined intervals, a branch circuit for by-passing said switch means, electromagnetic means having an energizing winding, an armature connected into said branch circuit and movable to one position

20 to open the branch circuit in response to energization of said winding and to another position to close the branch circuit upon deenergization of said winding to said source to energize said winding, means for connecting said winding when said switch means is closed, a discharging circuit into which said winding is connected and a condenser in said discharging circuit.

2. Electrical beacon equipment comprising an electric lamp, an electrical current source, an electrical circuit connecting the lamp and source, switch means for opening and

35 closing the circuit at predetermined intervals, a branch circuit for by-passing said switch means, electromagnetic means having an energizing winding, an armature connected into said branch circuit and movable to one position

40 to open the branch circuit in response to energization of said winding and to another position to close the branch circuit upon deenergization of said winding, means for connecting said winding to said source to energize said winding when said switch means is closed and for disconnecting said winding from said source when said

45 switch means is open and means for supplying current to said winding for a predetermined time when said switch means is open.

3. In electrical beacon equipment the combination with lamp changer mechanism of the type having a lamp carrier

50 provided with a plurality of electric lamps and movable to position the lamps successively in an operating position, of an electric motor for actuating said carrier, a source of electrical current, a motor circuit into which said motor and source are connected, a lamp circuit including one of said lamps and said source, an armature

55 connected into said motor circuit and movable to a position to close the motor circuit and to another position to open the same, means for yieldingly holding the armature in open position, an energizing winding in said lamp

60 circuit positioned to produce a magnetic flux tending to move the armature toward closing position, and an energizing winding connected in parallel with said one of said lamps and positioned to produce a magnetic flux tending to move the armature toward closing position, the resultant force of said magnetic fluxes on said armature being insufficient to move the armature toward closing position when said lamp circuit is closed.

4. In electrical beacon equipment the combination with lamp changer mechanism of the type having a lamp carrier

70 provided with a plurality of electric lamps and movable to position the lamps successively in an operating position, of an electric motor for actuating the carrier, a source of electrical current, a motor circuit into which the motor and source are connected, a lamp circuit including said source and one of said lamps, an armature

75

connected into said motor circuit and movable to one position to close the motor circuit and to another position to open the same, yieldable means yieldingly urging the armature toward open position, an energizing winding connected in parallel with said one of said lamps and positioned to exert a magnetic force on said armature to overcome said yieldable means to move the armature toward closing position and an energizing winding in said lamp circuit positioned to exert a magnetic force in opposition to the magnetic force exerted by said first mentioned winding to cause said yieldable means to hold the armature in open position when the lamp circuit is closed.

5. In electrical beacon equipment the combination with lamp changer mechanism of the type having a lamp carrier provided with a plurality of electric lamps and movable to position the lamps successively in an operating position, of an electric motor for actuating the carrier, a source of electrical current, a motor circuit into which the motor and source are connected, a lamp circuit including said source and one of said lamps, an armature connected into said motor circuit and movable to one position to close the motor circuit and to another position to open the same, yieldable means yieldingly urging the armature toward open position, a first energizing winding connected to said source and positioned to exert a magnetic force on said armature in a direction to move the armature toward closing position and a second energizing winding in said lamp circuit arranged in opposed magnetic relation to said first magnetizing winding and positioned to exert a magnetic force on said armature in a direction to move the armature toward closing position.

6. In electrical beacon equipment the combination with lamp changer mechanism of the type having a lamp carrier provided with a plurality of electric lamps and movable to position the lamps successively in an operating position, of an electric motor for actuating the carrier, a source of electrical current, a motor circuit including said source and one of said lamps, an armature connected into said motor circuit and movable to one position to close the motor circuit and to another position to open the same, yieldable means yieldingly urging the armature toward open position, a first energizing winding connected to said source and positioned to produce a magnetic flux in a direction and of sufficient strength to move said armature to closing position, a second energizing winding connected into said lamp circuit and positioned to produce a magnetic flux in a direction opposite to the direction of the flux produced by said first energizing winding, the resultant of the magnetic forces exerted on said armature by said windings when both of the windings are energized being insufficient to move the armature to closing position.

7. In electrical beacon equipment the combination with lamp changer mechanism of the type having a lamp car-

rier provided with a plurality of electric lamps and movable to position the lamp successively in an operating position, an electrical current source, a lamp circuit into which said source and the one of said lamps in said operating position is connected, switch means for opening and closing the lamp circuit at predetermined intervals, an electric motor for actuating said carrier, a motor circuit including said source and said motor, means for opening and closing the motor circuit and means for actuating said last named means to close the motor circuit when the lamp circuit has been open longer than the predetermined open interval of the lamp circuit.

8. In electrical beacon equipment the combination with lamp changer mechanism of the type having a lamp carrier provided with a plurality of electric lamps and movable to position the lamps successively in an operating position, an electrical current source, a lamp circuit into which said source and the one of said lamps in said operating position is connected, switch means for opening and closing the lamp circuit at predetermined intervals, an electric motor for actuating said carrier, a motor circuit including said source and said motor, means for opening and closing the motor circuit and means for actuating said last named means to close the motor circuit when the lamp circuit has been open longer than the predetermined open interval of the lamp circuit and to open the motor circuit upon reclosing of the lamp circuit.

9. In electrical beacon equipment the combination with lamp changer mechanism of the type having a lamp carrier provided with a plurality of electric lamps and movable to position the lamps successively in an operating position, an electrical current source, a lamp circuit into which said source and the one of said lamps in said operating position is connected, switch means for opening and closing the lamp circuit at predetermined intervals, an electric motor for actuating said carrier, a motor circuit including said source and said motor, means for opening and closing the motor circuit, means for actuating said last named means to close the motor circuit when the lamp circuit has been open longer than the predetermined open interval of the lamp circuit and to open the motor circuit upon reclosing of the lamp circuit, and means for opening the motor circuit when the lamp circuit has been open longer than the time required for each of said lamps to be moved successively into said operating position.
